BRACELET LOCKET

Alfred Corbi, Pawtucket, and Leo Bojar, Providence, R. I.; said Corbi assignor to said Bojar

Application July 22, 1941, Serial No. 403,506

8 Claims.

(CL 63—5)

Our present invention relates to the jewelry art, and has particular reference to bracelet constructions.

It is the principal object of our invention to devise a concealed pocket construction suitable for bracelets of the ornamental and the identification type.

Another object of the invention is to provide an openable compartment for a bracelet, which utilizes simple stamped parts and which is readily assembled.

Still another object is to utilize snap catch and latch parts which are integral with the separable parts of the openable compartment.

With the above and other objects and advantageous features in view, the invention consists of a novel arrangement of parts more fully disclosed in the detailed description following, in conjunction with the accompanying drawing, and more specifically defined in the claims appended thereto.

In the drawing:

Fig. 1 is a plan view of a bracelet embodying the invention;

Fig. 2 is a front view thereof;

Fig. 3 is a view similar to Fig. 2, the parts being separated to disclose the openable compartment;

Fig. 4 is a rear perspective view of the compartment top;

Fig. 5 is a front perspective view of the compartment base;

Fig. 6 is a rear perspective view thereof;

Fig. 7 is a section on the line 7—7 of Fig. 2;

Fig. 8 is a section on the line 8—8 of Fig. 2; and

Fig. 9 is a detail section showing the disengagement stops for the separable parts.

It has been found desirable to provide an openable, normally concealed compartment for a bracelet. To this end, we have provided two separable parts which slide together to form a concealed pocket compartment, the parts being attached to the bracelet ends.

Referring to the drawing, the bracelet 10, which is preferably of the expandable type, is provided with a compartment 11 made of two separable parts, a top 12, and a base 13.

The top 12, see Fig. 4, is preferably made of a single metal stamping and includes a cover 14, which may be ornamented as desired and may have an ornament 15 riveted or secured thereto; the top has two edges 16, 17, which are bent inwardly as illustrated to form two flanges 18, 19, which provide a slide runway. Each edge

5 has its front edge notched as indicated at 20, and has a punched-in dimple to provide a front stop 21; the rear of the cover is bent downwardly and then inwardly to provide a resilient depending tongue 22 which has a raised catch portion 23. The rear end of the top 12 is closed and has a bracelet end connection 24 secured thereto, which for the type of bracelet illustrated is provided with a pivot opening 25.

10 Slidably associated with the top 12 is the base 13, which, as illustrated in Figs. 5 and 6, comprises a lower portion 26 with its sides bent to form two edges 27 and again bent to provide slides 28, the rear ends of the slides having lateral stops 29, and the front end of the base having a transverse bar 30, which extends beyond the slides to provide two front stops 31, which are adapted to enter the notches 20. A strengthening cross bar 32 may be provided if desired. The 15 rear end of the lower portion is shaped and bent up to form a latch 33, see Fig. 5, and a bracelet end connection 34 is secured to or attached to the front of the base 13, provided with a pivot opening 35.

20 25 When the top and the base are assembled together, the slides 28 slide beneath the flanges 18, 19 and within the runway, and the stops 29 are movable between the closed ends of the top and the front stops 21; when the parts are in closed position the latch 33 rides over the catch portion 23, and the front stops 31 enter the notches 20 to wedge therein and retain the parts rigidly together. If desired, the front stops 31 and the notches may also function as inward stop parts.

30 35 The upstanding sides of the base provide a concealed compartment which may be utilized to hold a picture, a paper, or the like as desired; yet the construction does not appear to provide an openable container at casual inspection, as the parts rigidly engage. Moreover, there are only two stampings, whereby the cost of manufacture and assembly is greatly reduced.

40 45 Although the disclosure is specific to bracelets, the invention may be readily made applicable to jewelry in general, such as brooches, buckles, rings, earrings, pendants, and the like, by changes within the knowledge of a skilled jeweler. Changes in the size, shape, dimensions, and ornamentation of the parts may also be made to suit 50 the requirements for different bracelet and jewelry arrangements, without departing from the spirit and the scope of the invention as defined in the appended claims.

We claim:

1. In combination, a bracelet, and a compart-

ment consisting of a top and an interengaging, relatively slidable base, the top being secured to one bracelet end, and the base to the other bracelet end, said top and base having cooperating catch and latch parts.

2. In combination, a bracelet, and a compartment consisting of a top and an interengaging, relatively slidable base, the top being secured to one bracelet end, and the base to other bracelet end, said top having flanged edges forming a runway, and said base having side slides slideable within said runway, said edges and slides having parts engageable to limit movement of said base in said top.

3. In combination, a bracelet, and a compartment consisting of a top and an interengaging, relatively slidable base, the top being secured to one bracelet end, and the base to the other bracelet end, said top having flanged edges forming a runway, and said base having side slides slideable within said runway, said edges and slides having parts engageable to limit movement of said base in said top, said base and top having interengaging parts to rigidly hold said base and top together when in closed position.

4. In combination, a bracelet, and a compartment consisting of a top and an interengaging, relatively slidable base, the top being secured to one bracelet end, and the base to the other bracelet end, said base having one end shaped as an integral catch and said top having its corresponding end shaped as an integral latch.

5. In combination, a bracelet, and a compartment consisting of a top and an interengaging, relatively slidable base, the top being secured to one bracelet end, and the base to the other bracelet end, said base having one end shaped as a

resilient integral catch and said top having its corresponding end shaped as an integral latch.

6. In combination, a bracelet, and a compartment consisting of a top and an interengaging, relatively slidable base, the top being secured to one bracelet end, and the base to the other bracelet end, said top having flanged edges forming a runway, and said base having side slides slideable within said runway, said edges and slides having parts engageable to limit movement of said base in said top, said base having one end shaped as an integral catch and said top having its corresponding end shaped as an integral latch.

7. In combination, a bracelet, and a compartment consisting of a top and an interengaging, relatively slidable base, the top being secured to one bracelet end, and the base to the other bracelet end, said top having flanged edges forming a runway, and said base having side slides slideable within said runway, said edges and slides having parts engageable to limit movement of said base in said top, said base and top having interengaging parts to rigidly hold said base and top together when in closed position, said base having one end shaped as an integral catch and said top having its corresponding end shaped as an integral latch.

8. In an article of jewelry, a top part having inwardly directed flanges forming a runway, and a base part having side slides positioned in said runway, said parts having interlocking means to limit closing and separating movement, snap catch and latch means, and also having wedging means interengaging when the parts are in closed position.
